APPARATUS FOR MAKING A BELT SPLICE

Filed Feb. 9, 1932

UNITED STATES PATENT OFFICE

WILLIAM J. SCULLEY, OF PALMYRA, NEW JERSEY

APPARATUS FOR MAKING A BELT SPLICE

Application filed February 9, 1932. Serial No. 591,917.

This invention relates to apparatus for and method of making a belt splice, and has for an object to provide an improved type of splice in an improved manner and by an improved type of apparatus.

A further object of the invention is to provide an apparatus embodying means for clamping a belt end and holding it rigidly within a housing, with improved means for producing a slit wholly within the belt end, entirely surrounded by walls of the belt material.

A further object of the invention is to provide a device having means for clamping a belt end and holding the same in fixed position, with a knife or lesser width than the width of the belt, positioned to be driven into the end of the belt, but not severing the belt to its margin in any direction, and with further means for forming perforations through the belt at right angles to the cut of the knife.

A further object of the invention is to provide the method of making a belt splice consisting in clamping a belt end into an apparatus for providing a slit into the end thereof, and completing the belt splice by inserting a dowel into the slit formed by the apparatus, with fastening means inserted through the belt and the dowel.

A further object of the invention is to provide the method of making a belt splice consisting in clamping the belt ends separately and individually to hold them against movement, driving a knife longitudinally into the ends of the belts so held to provide a slit or socket into the end of the belt and forming perforations through the belt and through the slit so formed, inserting a dowel into the slits of each end, and inserting fastening means through the perforations of the belt ends and the dowel.

The invention therefore comprises as an apparatus, a body having a clamping device for receiving and clamping the end of the belt and holding it permanently to position, with a knife positioned to be driven into the end of the belt for forming a slit therein, a perforating tool to be inserted through the end of the belt transacting the slit so formed,

removing the belt ends from the clamping position, inserting a dowel into the slit so formed, such dowel being preformed with perforations registering with the perforations of the slit, and completing by fastening members inserted through the perforations of the belt ends and dowel. 55

The drawing illustrates an embodiment of the invention, and the views therein are as follows:

Figure 1 is a view of the apparatus in side elevation,

Figure 2 is a view in end elevation; as indicated by arrow 2 at Figure 1,

Figure 3 is a top plan view as indicated by arrow 3 at Figure 1,

Figure 4 is a longitudinal sectional view, taken on line 4-4 of Figure 3,

Figure 5 is a transverse sectional view, 70 taken on line 5-5 of Figure 3,

Figure 6 is a transverse sectional view, taken on line 6-6 of Figure 1, the plans of Figures 5 and 6 being the same, but looking in opposite directions, 75

Figure 7 is a plan view of the knife and plunger, and

Figure 8 is a view partly in elevation, and partly in section of the completed belt splice.

Like characters of reference indicate corresponding parts throughout the several views.

The apparatus which forms the subject matter of the present application comprises a body made up of several sections. The base section 10, carries rigidly secured thereto, the upper sections 11. At the end, a separate section 12 is provided. The section 11 is permanently secured to the base 10 as by screws 13, while the section 12 is employed as a clamp, and such clamping is brought about by any approved clamping means, as the screws 14.

At the end opposite the clamping section 12, a section 15 is secured to the base in any approved manner. Screws 16 are shown for the purpose, but it is obvious that this connection may be brought about in any manner as the connection is permanent.

The section 15 is drilled to form a passage 17 for the receipt of the shank 18 of the knife 100

19. A head 20 is preferably provided upon the shank 18.

A lever 20' is provided, fulcrumed at 20''. This lever is provided with a bifurcated end 5 18' which sets astride the shank 18. When the shank 18 is driven inwardly by impact upon the head 20, the lever 20' will swing against the body 15. After the cut has been made, a blow applied to the lever 20 will retract the knife from its cut.

The base 10 and the upper section 11 are provided with registering perforations 21 and 22 through which a perforating tool 23 is passed.

15 In operation, and carrying out the method of making the belt splice, the belt ends 24 and 25 are separately and individually inserted into the opening 26 by loosening the clamping member 12. In the specific arrangement 20 shown, this is brought about by loosening the screws 14. The belt end is inserted into the device until the end abuts against the end section 15. The clamping member 12 is now clamped tightly upon the belt section. As 25 shown, the device is arranged for operating upon an elliptical or oval belt. It is understood, of course, that the shape of the opening 26 in the device will correspond to the shape 30 of the belt to be operated upon, or conversely the shape of the belt will be made to correspond to the opening, and showing this as oval, or elliptical, is no limitation upon the invention. The passage 26 is, however, constricted by the block 14 so that at that position 35 the belt is firmly clamped, while the section nearer the knife 19 not being compressed, will allow the insertion of the knife.

The insertion of the belt into the opening 40 will force the knife 17 within the socket formed in the section 15, or this may be withdrawn into that position before the belt is inserted. In any case, the knife will occupy the position shown at Figure 4 when the belt 45 has been inserted into contact with the section 15.

The belt being clamped and held rigidly by 50 the block 14 forming the constriction of the passage 26, the knife 19 is driven into the end of the belt by force applied to the head 20. This may be by pressure or by hammer blows 55 upon the head as found convenient. In any event, it will be noted that the width of the knife 19 is considerably less than the corresponding width of the belt so that the knife, when driven into the belt end, will form a wall entirely around the slit provided by the knife being so inserted. The knife having been driven in, is withdrawn from the cut 60 thus made by a blow applied to the lever 20' and with the knife so withdrawn, the perforating tool 23 is inserted, first through the one, and then the other of the registering perforations 21 and 22, and through the belt enclosed therein transacting the cut produced 65 by the knife. The edge or marginal walls of

the belt, after such slitting and perforation, are indicated at Figure 8 by the numeral 27. Into the slit formed by the insertion of the knife 19, a flat dowel 28 is inserted. This dowel in practice, will as at present contemplated, be constructed of thin sheet metal, but the invention is of course, not limited to the material. The dowel is preformed with perforations corresponding to and registering with the perforations 21 and 22 of the apparatus, and bolts, rivets, or the like, indicated at 70 29, will be inserted through the registering perforations of the belt ends and the dowel. 75

Preferably, though not necessarily, the inner side of the belt will receive countersunk heads of these fastening members so that the surface of the belt making contact with the pulley will be smooth.

80 The exterior of the belt is of less importance, and this may be made by nuts upon threaded bolts. The threaded bolts and nuts have the advantage that they may be readily displaced when it is necessary to shorten the belt. For shortening the belts, of course, it is necessary to remove only the dowel from one end and to repeat the operation only so far as one end of the belt is concerned.

85 Of course, the apparatus for making a belt splice, herein illustrated, may be modified and changed in various ways without departing from the invention herein set forth and hereinafter claimed.

90 The invention is hereby claimed as follows:

1. An apparatus for use in making belt 100 splices comprising a clamping member, a knife positioned to be driven into the end of a belt clamped by the clamping member, and guides for directing tools for forming transverse perforations through the belt.

2. An apparatus for use in producing belt 105 splices consisting in a body having a passage therein, means to clamp a belt end within the passage, a knife of lesser width than the width of the passage positioned in alignment with the major axis of the passage, and means through which stress may be applied to drive the knife into the inserted belt end.

3. An apparatus for use in producing belt 110 splices comprising a body having a longitudinally disposed passage therein corresponding in transverse contour to the transverse contour of the belt, means to clamp the belt end within the passage, a knife positioned in alignment with the major axis of the passage and of lesser width than the passage, and means through which stress may be applied to the knife to force it into a belt end clamped within the passage.

4. An apparatus for use in producing belt 115 splices comprising a body having a passage therein complimentary to the contour of the belt to be operated upon, means to clamp the belt end within the passage, a knife mounted to slide within the passage and of lesser width than the passage, means through which stress 120 130

may be applied to force the knife into the passage, said body being provided with guides for positioning a perforating tool relative to the belt, and a perforating tool adapted to be forced through said guides.

5. An apparatus for use in producing belt splices comprising a base, a section mounted as a clamping part relative to the base, said base and clamping part cooperatively provided with a passage complimentary to the belt to be operated upon and adapted to clamp a belt end firmly therein and with an opening in alinement with the passage, and a knife mounted to slide in said opening and into said passage and guided by said opening to travel along the axis of the passage, the knife being of less width than the corresponding dimension of the passages.

6. An apparatus for use in producing belt splices comprising a base, a section mounted as a clamping part relative to the base, said base and clamping part cooperatively provided with a passage complementary to the belt to be operated upon and adapted to clamp a belt end firmly therein and with an opening in alinement with the passage, and a knife mounted to slide in said opening and into said passage and guided by said opening to travel along the axis of the passage, the knife being of less width than the corresponding dimension of the passage, the base and superposed part being provided with spaced openings serving as guides for a perforating tool to transect the passage.

35 In testimony whereof I have signed my name to this specification.

WILLIAM J. SCULLEY.
